UNITED STATES PATENT OFFICE.

AUGUST C. KLEIN, OF JAMAICA PLAIN, MASSACHUSETTS, ASSIGNOR TO STONE & WEBSTER, INC., OF BOSTON, MASSACHUSETTS, A CORPORATION OF MASSACHUSETTS.

METHOD OF MAKING CARBURETED WATER GAS.

Application filed November 18, 1921. Serial No. 516,230.

- This invention relates to the manufacture of carbureted water gas in the usual gas making set including a generator, carburetor, and superheater and has special reference to the manufacture of carbureted water gas in which a fuel having a substantial carbon depositing content, as Californian and Mexican crude oils, is employed to enrich the water gas.
- 10 The usual gas making process comprises a "run" and "blow". During the run, steam is admitted to the highly heated carbonaceous fuel in the generator to form water gas. The resultant water gas is passed into, and through, a carburetor containing highly heated brick checker work and from thence to a similarly constructed and highly heated superheater. During the run oil is sprayed into the carburetor and is vaporized therein and converted into fixed gases which mix with and enrich the water gas passing through the carburetor. The final fixing of the oil vapor occurs in the superheater. After a short period, usually about 25 three to four minutes, the temperatures in the generator and carburetor become so reduced that gas can not be made efficiently and a blow is begun. For the blow, steam is turned off from the generator and oil from 30 the carburetor and air is forced through the generator to burn with and reheat the fuel in the generator. The products of combustion, known as blast or producer gases, are passed through the carburetor and superheater and serve to reheat both. Air is admitted into the stream of producer gas as it enters the carburetor and burns with the producer gas and the resultant heat is utilized to restore the temperature of the carburetor and superheater. The blow usually takes about two to three minutes.
- When the temperatures in the apparatus have been restored, air is turned off from the generator and also from the carburetor and another run is begun by admitting steam again to the generator and oil to the carburetor.
- It has been found that when certain enriching fuels are used, as Californian and Mexican oils, a substantial quantity of carbon is deposited upon the carburetor checker brick, and that the carbon deposit, if permitted to remain and to become highly heated during succeeding blows, will combine with the sulphur which usually exists in the enriching fuels especially those specifically mentioned, or possibly in the enriched water gas, to form substantial quantities of carbon disulphide, a compound detrimental to the quality of the carbureted water gas. For this reason, it is desirable to remove the carbon deposit from the carburetor before each gas making run whereby to manufacture a gas of low carbon disulphide content.
- It has been the practice to burn the carbon deposit in the carburetor after the generator blasting period by admitting air into the carburetor after the air has been turned off in the generator and the production of producer gas has ceased. The air will unite with the heated carbon deposit and burn to carbon monoxide and carbon dioxide with the evolution of considerable heat, which has been found to accelerate the deterioration of the carburetor checker brick through chipping and splitting.
- An object of this invention is a process for making carbureted water gas in which the carbon deposit in the carburetor is burned out before the generator blasting operation. At the end of the run, the brick work is comparatively cool. The heat resulting from burning out the carbon deposit raises the temperature of the cool brick work and may even superficially heat the surface of the bricks to which it is attached, yet the temperature rise usually is not nearly so great as when the burning operation is carried out after the generator blasting operation when the bricks are already heated to incandescence. When the generator air blast is turned on, at the end of the carbon burning operation, the entire brick work is bathed in the relatively cool blast gases. During the continuance of the blasting any excess heat on the surface of the brick has time to penetrate or be conducted into the brick, so that the brick becomes uniformly heated. Excess heat on the surface of the brick checker work may also be given up to the surrounding blast gases so that at the end of the air blasting operation, the top courses, and also the lower courses, of the brick work are uniformly heated with the result that, when oil is sprayed into the carburetor during the following run, there may be a substantial reduction of chipping and splitting of the bricks and the carbon de-

posed during the succeeding run may be substantially less than will be the case when the coke is burned after the generator blasting operation.

5 The usual gas making set is provided with an air blast pipe of relatively large cross-section extended from the blower or other source of pressure air supply to the base of the generator, and an upper pipe extended from the top of the generator to the top of the carburetor and a lower pipe extended from the base of the generator and communicating with said upper pipe. The pipes connecting the generator and carburetor are so arranged that water gas can be conducted into the carburetor from either the top or bottom of the generator. The upper pipe is also used to conduct generator blast gases from the top of the generator to the top of the carburetor. The set is also provided with an air blast pipe of relatively small diameter as contrasted with said upper and lower pipes, and said pipe is extended from the source of pressure air to 20 the carburetor for the purpose of supplying air to burn the generator producer gases in the carburetor to reheat it.

While the capacity of the carburetor blast pipe is sufficient to supply the air needed for burning with the producer gas it may be of insufficient capacity to supply the large amount of air required to burn out rapidly and effectively the carbon deposit in the carburetor and, when used, the carbon burning operation must be continued for a considerable period of time in order to burn out the carburetor cleanly, and therefore the twenty-four hour gas making capacity of the set is reduced.

40 A further object of this invention is a method of operating the usual gas making set whereby relatively large amounts of air may be supplied to the carburetor for the carbon burning operation as contrasted with the air capacity of the usual carburetor blast pipes, and without alteration of or addition to the usual gas making set.

In carrying out this object of the invention, I pass air directly from the source of pressure air into the base of the generator and withdraw air from the base of the generator through the lower pipe connecting with the base of the generator by which it will be conducted into the top of the carburetor and burn with the carbon deposits; and I may at the same time, and preferably do also pass air through the carburetor blast pipe into the carburetor to augment the supply for the carbon burning operation. I also close the valve in the pipe extending from the top of the carburetor to the generator so that air will not be forced through the bed of fire in the generator. In this manner a relatively great amount of air 55 may be passed through the carburetor in a

relatively short period of time so that the carbon burning operation is rapidly carried out.

Fig. 1 is a side elevation, partly in section, of a gas making set adapted for the performance of the invention.

Fig. 2 is a perspective detail of the top courses of brick checker work in the carburetor illustrating the manner in which the carbon deposit is formed.

The water gas making set here shown, and adapted for the performance of the invention, is of more or less common construction and includes the water gas generator 10, the carburetor 11, and the superheater 12. Air 80 is supplied to the generator from a source of pressure air, as the blower 13, through the pipe 13^a; and said pipe has a valve 13^b therein by means of which the flow of air may be controlled. A pipe 14 of relatively 85 large diameter, having a valve 15 therein extends from the top of the generator to the top of the carburetor and a similar lower pipe 16 having a valve 17 therein extends from the base or ash pit of the generator 90 and connects with the pipe 14 on the carburetor side of the valve 15 in said pipe. This arrangement of pipe provides means whereby the direction of making gas through the generator may be reversed when desired. A pipe 18 connects the bases of the carburetor and the superheater and serves to conduct gas from one to the other. A stack pipe 19 is in communication with the top of the superheater and is provided with a stack 100 valve 19^a on the end thereof. During an air blasting period, the stack pipe valve will be open and the products of combustion will escape to the atmosphere, preferably, however, first passing through a waste heat 105 boiler 19^b. During a gas making run stack valve 19^a will be closed and the carbureted water gas will pass from the top of the superheater through the pipe 20 and the water seal 21 into a gas holder, not shown.

The carburetor is provided with a carburetor air blast pipe 22 of relatively small diameter as compared with the diameter of the pipes 13, 16, and 14. Said pipe 22 is in communication with the blower 13 through the pipe 13^a and usually with the pipe 14 adjacent the carburetor. A valve 23 in said pipe serves to control the flow of air therethrough.

The carburetor contains the brick checker 120 work 24 through which the vapors of the enriching fuel pass commingled with water gas from the generator to be fixed into permanent gases. Fuel for enriching the water gas is admitted to the top of the carburetor 125 through the pipe 25 and a valve 26 therein serves to control the flow of the enriching fuel.

The generator is provided with a steam pipe having the lower valve controlled 130

branch 27 and the upper valve controlled branch 27^a arranged to admit steam respectively either below or above the fuel bed in the generator.

5 The customary method of manufacturing carbureted water gas is substantially as follows:

During a gas making run, the generator blast valve 13^b, the carburetor blast valve 10 23 and one of the valves 15 and 17 is closed. Assuming the valve 17 to be closed, steam is admitted through the steam branch 27 to the base of the generator and passes upwardly through the highly heated fuel body 15 therein, which fuel body has previously been highly heated by air blasting. Water gas is formed in the generator by the action of the steam on the highly heated fuel and passes through the pipe 14 into the top of 20 the carburetor and thence flows downwardly through the checker work 24 therein and through the connecting pipe 18 into the base of the superheater. Oil is sprayed onto the top of the checker work in the carburetor through the pipe 25 to enrich the water gas.

At the completion of the run, the generator blast valve 13^b is opened and air is forced through the cooled bed of fuel in the 30 generator to burn therewith to reheat it.

The producer gas formed in the generator passes through the pipe 14 into the top of the carburetor. The carburetor blast valve 23 is opened and air is admitted through 35 the pipe 22 into the producer or blast gas as it passes into the carburetor and burns therewith and the resultant heat raises the temperature of the checker work in the carburetor and superheater. During the blasting period, the oil is turned off. After the temperatures have been suitably re-established, a second gas making run is begun.

When certain oils, as Californian and Mexican, having a substantial carbon depositing content are employed as enriching fuels, the carbon deposit will collect on the checker brick. The deposit will gradually form upon the first two courses as at A, Fig. 2, and at a slower rate upon the lower courses.

50 It has heretofore been the practice to burn out the carbon deposit in the carburetor after the generator air blasting period or just previous to the next water gas making run by closing the generator valve 13^b and continuing to admit air to the carburetor through the carburetor blast pipe 22 as above described.

As has been set forth, the removal of the carbon deposit at this period results in 60 the chipping and crumbling and deterioration of the checker work in the carburetor by reason of the sudden cooling action of the oil sprayed upon the highly heated bricks. By burning out the carbon deposit 65 after each run and before the generator

blasting operation, in accordance with my invention, I find that the brick checker work may be relatively free from deterioration for relatively long periods and consequently a considerable saving of expense may result 70 by reason of less frequent replacements of the checker work.

While air for burning out the carbon deposit may be supplied through the pipe 22, I find that much better results are obtained, and in a shorter period, by operating the gas making set so that air is supplied mainly from the relatively large pipe 13^a to the base of the generator and thence through the pipe 16 into the carburetor. Inasmuch as the capacity of said pipe line is considerably greater than that of the carburetor blast pipe 22, the period required for the carbon burning operation is considerably reduced whereby the twenty-four 80 hour capacity of the set is enhanced. I find further that, by reason of the greater capacity of said pipe line and consequently the ability to direct large volumes of air through the carburetor, the carbon burning 85 is more efficiently performed and a cleaner carburetor results as the air supply is ample to search and burn out remotely disposed carbon particles, and the finished carbureted water gas consequently may have a 90 reduced carbon disulphide content.

In operating the gas making set in accordance with my invention, I prefer to proceed as follows:

During the water gas making run the 100 stack valve 19^a, the generator blast valve 13^b and the carburetor blast pipe 22 will be closed and one of said valves 17 and 15 will be closed as before. Steam is admitted in the generator to form water gas and the 105 water gas passes into the carburetor and mixes with the vapors and gases of oil sprayed into the carburetor through the pipe 25 as is more or less usual practice. At the end of the run, assuming valve 15 to 110 be open and valve 17 closed, oil and steam are shut off and the stack valve 19^a opened. The air valves 13^b and 23 are then opened, and valve 17 immediately opened and valve 15 closed. Air now flows through pipe 22 115 into the carburetor and also through the base of the generator and into and through pipe 16 and into the top of the carburetor and downwardly through the carburetor. No air is forced through the generator fire for 120 the reason that valve 15 is closed. The air supplied through pipes 16 and 22 into the carburetor unites with the heated carbon deposit on the checker work and burns with 125 it. The heat resulting from the combustion of the carbon deposit in the carburetor raises the temperature of the carburetor and also of the superheater. When the carbon deposit has been burned out, valves 15 and 17 are adjusted for the generator blasting 130

operation, valve 15 being opened and valve 17 closed. Air is now forced through the fuel bed in the generator to burn with and reheat it and the producer gas formed passes 5 through the pipe 14 into the top of the carburetor. If the carburetor has been insufficiently heated by the combustion of the carbon deposit therein, and the amount of carbon deposited may vary with the particular 10 oil employed as the enriching medium, then air will continue to be admitted through the carburetor blast pipe 22 to burn with the producer gas in the carburetor and elevate still further the temperature of the carburetor and superheater. If, however, the 15 temperature in the carburetor and superheater has been raised sufficiently high by the combustion of the carbon deposit in the carburetor then, preferably, air is not admitted to the carburetor through the pipe 22. With this latter condition, I prefer to 20 force air through the generator at a relatively greater rate than has heretofore been customary whereby to burn the fuel in the generator more efficiently and raise the temperature of the fuel bed to the required degree in a shorter time and thereby reduce the time required for the blasting operation and increase the daily capacity of the set. 25

30 At the end of the air blasting period, the generator blast valve 13^b is closed and valves 15 and 17 properly adjusted to secure the desired direction of steam flow through the generator and steam turned into the generator through one of the steam branches, the particular one depending upon which of said valves 15 and 17 is open, and a new gas making run is begun.

35 The term "carbon" as herein employed denotes the carbon which is separated from the enriching fuel and deposited in the carburetor and this carbon may have associated with it other solids as sulphur compounds.

40 I claim:

45 1. The steps in the method of making carbureted water gas with an oil having a substantial carbon depositing content and in a gas making set including a generator and carburetor, which consists in reheating the 50 carburetor after the usual combined steam

and gas enriching run by burning out the carbon deposit in the carburetor before each generator air blasting operation by a blast of free air passed through the carburetor in the direction of gas making, and then additionally heating the carburetor by immediately air blasting solid fuel in the generator and passing the hot blast gases through the carburetor.

2. The method of making carbureted 60 water gas with an oil having a substantial carbon depositing content and in a gas making set including a generator and carburetor, which consists of the following three steps, in the order named; first, air blasting 65 fuel in the generator to heat the fuel and passing the hot blast gases into the carburetor; second, passing steam into the heated fuel in the generator to form water gas and passing the water gas into and enriching the water gas in the carburetor; and third, burning the carbon deposit out of the carburetor with air and excluding the products of combustion from the generator.

3. The method of making carbureted 75 water gas with an oil having a substantial carbon depositing content and in a gas making set including a generator and a carburetor, which consists in the immediately repeated performance of the following 80 steps, in the order named; first, in forcing air through the generator fuel bed to heat the fuel and form producer gas, passing the producer gas into and burning it in the carburetor to heat the carburetor; second, in 85 admitting steam to the heated fuel bed in the generator to form water gas and passing the water gas through the carburetor and spraying oil into the carburetor to enrich the water gas; and third, shutting off 90 steam from the generator and oil from the carburetor when the generator fuel bed becomes cooled and passing air through the carburetor to burn off the highly heated carbon deposit in the carburetor and excluding 95 the products of combustion from the generator.

In testimony whereof, I have signed my name to this specification.

AUGUST C. KLEIN.
